UNITED STATES PATENT OFFICE.

HARRY F. SPOTTS, OF RIVERSIDE, CALIFORNIA.

SHIM-FILING CLAMP.

Application filed March 18, 1925. Serial No. 16,384.

This invention relates to a shim filing clamp.

An object of the invention is to provide a clamp affording a base for the reception of a shim to be filed and having complementary jaws adapted to secure the shim firmly in a horizontal position and to permit a thickness of the shim to extend above the upper surface of the jaws so that the shim 10 may be filed to reduce it in thickness.

A further object of my invention is to support a flat shim on its lower face while the opposite edges are being gripped by gripping jaws, the shim extending slightly 15 above the surface of said jaws, whereby in filing the shim it is suitably supported underneath as well as being gripped by the jaws.

The application of this operation can be 20 readily recognized by machinists who are accustomed to adjusting bearings and the like.

The shim filing clamp shown herein contemplates adaptation to an ordinary vise 25 and may be readily adjusted to accommodation of shims of different sizes and may be tightened in the vise to hold any shim within a wide range of sizes.

Other objects and advantages will be 30 made manifest in the following specification of an embodiment of the invention illustrated in the accompanying drawings, in which:

Figure 1 is a perspective of the shim filing clamp in its relation to an ordinary 35 working vise,

Fig. 2 is a vertical sectional view of the shim filing clamp, and

Fig. 3 is a perspective of the shim filing 40 clamp upside down, to better illustrate the construction.

The details of construction are as follows:

A pair of complementary gripping members 2 and 3 which are slidable in their relation with each other are formed as follows:

The gripping member 2 constitutes a base or a block 4 upon which is transversely and centrally mounted a rectangular member 5 and upon the rectangular member 5 is imposed transversely a jaw 6. The jaw 6 is comparatively thin so that an ordinary shim will stand considerably above the 50 jaw member and it is preferably made of very hard steel which will not be sus-

ceptible to a file. The gripping edge 7 of the jaw 6 is straight and may be somewhat beveled with its upper portion projecting forwardly so as to better grip the edge of a shim 8. A lug 9 is formed on the inner edge of the block 4 and extends longitudinally of and parallel to the member 5.

The second gripping member 3 comprises a base or block 10 similar to block 4, having a lug 11 co-extensive with lug 9 and upon the upper face of the block 10 are mounted a pair of side members 12 and 13 which are of equal thickness with the member 5 and are separated sufficiently so that the member 5 may slidably operate between the members 12 and 13. An expansion coil spring 14 is disposed between the block 4 and the block 10, being held in place by the lugs 9 and 11, its office being to yieldably 75 separate the gripping members 2 and 3. Imposed upon the upper face of the side members 12 and 13 is a second jaw 15 of equal thickness to jaw 6 and upon the same plane. The jaw 15 is recessed in a semi-circular fashion as at 16 to provide for the reception of the curved portion of the shim 8 and the gripping edge of the jaw 15 may be also beveled slightly so that its upper edge may more firmly grip the edge of the 80 shim 10. The parts necessary to be rigid with each other may be secured by riveting or other suitable means.

In the operation of the invention the shim 8 which is to be filed is placed upon the seat 90 20 which includes the upper faces of both the central member 5 and the side members 12 and 13. The gripping members 2 and 3 are then compressed toward each other against the action of the spring 14, the blocks 4 and 10 being placed within the jaws of an ordinary vise 21. The vise may 95 then be tightened by means of the screw 22 and the jaws of the vise will exert an opposite pressure upon the blocks 4 and 10, thereby drawing the jaws 6 and 15 toward each other and consequently firmly gripping the shim 8 between them. It will be noted 100 that the blocks 4 and 10 are of sufficient thickness to be properly gripped by the vise so that the side members 12 and 13 and the central member 5 may be extending slightly above the jaws of the vise in order 105 that they may be free to slidably work for the purpose of contracting the gripping members.

When the jaws of the vise are drawn

apart the opposing gripping members of the filing clamp will be automatically separated by the action of the spring 14 and the shim 8 may be readily removed without taking 5 the filing clamp from the vise 21.

It will thus be seen that a shim may be placed on the shim filing clamp as shown in Fig. 1, the shim being supported on its flat surface by the central member or seat 10 20 and also by the side members 12 and 13, while the edge of the shim is being gripped by the jaws 6 and 15. Therefore in filing a shim there is no opportunity for the shim to spring up and down and hence allow filing 15 in the manner desired.

Various changes may be made without departing from the spirit of the invention as claimed.

What is claimed is:

20 1. A shim filing clamp comprising in combination a base block, a flat central rectangular member secured thereto above the block, a second base block, a pair of flat side members attached thereto above 25 said block and slideable on the outside of the rectangular member, and thin gripping jaws on the top of the rectangular member and the side members, the rectangular member and side members being adapted to support the flat side of a shim, the gripping jaws being adapted to engage the edge of a 30 shim, the base blocks being adapted to be secured in the jaws of a vise.

2. A shim filing clamp comprising in

combination a base block, a flat centrally mounted rectangular member secured to said block on the upper surface thereof, a second base block, a pair of flat side members attached to opposite ends of the second base block at the top thereof, said pair of side members being slideable on the outside edges of the central rectangular member, and thin gripping jaws attached to the central rectangular member and to the pair of side members adapted to grip a shim or the like whereby the shim may rest on the centrally mounted rectangular member and on the pair of side members, said base blocks being adapted to be gripped by the jaws of a vise or the like. 35 40 45 50

3. A shim filing clamp comprising in combination a central flat rectangular member, a pair of flat side members slideable on each side thereof, a flat thin jaw attached to the central member, a flat thin jaw attached to the side members, said jaws and the upper surfaces of the center and side members being positioned to support a shim resting flat on the side members and the central member and to be engaged edge-wise by the jaws, means whereby the jaws may be moved towards and from each other and side members slid longitudinally of the central member. 55 60

In testimony whereof I have signed my name to this specification. 65

HARRY F. SPOTTS.
